CARRIAGE-STOP MECHANISM FOR TYPE-WRITERS.

1,091,010.

Specification of Letters Patent. Patented Mar. 24, 1914.

Original application filed February 7, 1901, Serial No. 46,379. Divided and this application filed November 15, 1901, Serial No. 82,442. Renewed August 30, 1913. Serial No. 787,519.

To all whom it may concern:

Be it known that I, ENOS S. NEWMAN, a citizen of the United States, residing at Washington, in the District of Columbia, have invented certain new and useful Improvements in Carriage-Stop Mechanism for Type-Writers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to typewriting machines and the object thereof is to provide therefor improved carriage stop mechanism, such stop mechanism being particularly adapted for use in connection with a combined typewriting and adding machine for which I have made application for Letters Patent of the United States by application filed on February 7, 1901, Serial No. 46379 (of which this application is a division), although such stop mechanism is capable of use in a typewriting machine when used separately from said adding machine.

In the present and illustrated embodiment of my invention I have shown and will hereinafter describe the same in connection with the well known Burroughs adding machine, made in substantial accordance with Letters Patent of the United States Nos. 504,963, and 505,078 granted to William S. Burroughs on the 12th day of September, 1893.

In the drawings Figure 1 represents a rear elevation partly broken away of the adding and typewriting machine connected together for conjoint operation, parts being broken away; Fig. 2 represents a side elevation as seen from the left side of the two machines operatively connected, and Fig. 3 represents a view, on a larger scale than Fig. 2, showing in dotted lines the escapement rack lifted for tabulating.

Like numerals indicate the same parts wherever they appear in the several figures of the drawing.

Referring to the drawings by numerals,

1 (Fig. 2) indicates the left hand side of the case of the adding machine, 2 the top of the case, and 3 the keys of the keyboard of such machine. The keyboard, and in fact all of the mechanism of the typewriting machine except the carriage, is in this instance located to the left of the adding machine and close against the side 1 of the case thereof. Of the typewriting machine, the top is indicated at 4 and the keys of the keyboard at 5, the keys 3 and 5 of both machines being marked with letters and characters such as will appear in the machine when set up for practical use. The carriage of the typewriting machine is arranged to travel laterally, in this instance behind both machines, for the reason that in the type of adding machine illustrated the printing point is in the rear, but it will be readily understood by those familiar with the art that the position of the carriage may be changed to suit the style of adding machine used.

Inasmuch as the typewriter key elements and mechanism for making the typewriting impressions are concerned only in a general way with the stop mechanism which constitutes the present invention, it will suffice to state that each of the keys 5 of the typewriter is operatively connected with a type bar 21 by a train of mechanism comprising an elbow lever 9 reciprocated by the stem of such key, a rod 11, a movable reed-bar 12, a link 14, a multiplying lever 15, and a rod 19 pivoted to such type bar. The type bars are so arranged that all the type will strike the platen in the horizontal line of the printing point of the adding machine and to the left thereof at a distance depending upon the position of the paper carriage.

27 indicates brackets projecting rearwardly and upwardly from the back of the machine and carrying a track 29 upon which is mounted, on ball-bearings 30, the carriage 31, the balls being held in position by screws 32 (see Fig. 3), the track, and consequently the carriage, lying in a horizontal plane adjacent to the rear, or that face of the machine in which the printing point is located. Upon the carriage 31 are brackets 33 which, by pivots 34, carry the end plates

35, in which the platen or roll 24 is journaled, and which support other mechanism to be hereinafter mentioned.

36 indicates a rack in the rear of the carriage, the teeth of which point downward, said rack resting on rollers 37 journaled in brackets 38, mounted on a rocking bar or shaft 39 parallel with the rack and pivoted on its longitudinal axis in brackets 40 projecting rearward and upward from the track supports 27. Upon the upper face of the rack 36 is a lug 41. The brackets 40 are extended above the journals of the rocking bar 39 and in their upper ends carry a rigid stationary bar 42 (which I denominate the tabulating rail) provided on its front and rear edges with graduated notches 43 to receive an adjustable stop or pawl 44 which, when the rack 36 is in its upper position, 20 will engage the lug 41 and stop the travel of the rack at any predetermined point to which the stop 44 has been adjusted. The rack 36 is mounted in the ends of bars 45 swinging from the pivots 34 and its normal 25 position is such as to permit the lug 41 to pass under stop 44; but to raise it up, so that the stop will be in the path of the lug, the rock bar 39 is provided with a pendant lever-arm 46 connected by rod 47 with a lever 30 48 pivoted at 49 to the inside of the front of the case of the machine and provided with a push key or bar 50 at its upper end projecting through the front of the machine. When the bar or key 50 is pushed inward the lever arm 46 is pulled forward, the rock-bar turned and the rack thrown up to bring the lug 41 in the path of the stop 44. This mechanism is best shown in Fig. 2 and is only intended for use to permit the operator 40 to quickly shift the carriage to a predetermined point, the usual longitudinal feed of the carriage to the left being accomplished by means of a spring (not shown) in a drum 51 connected to the carriage by a 45 cord 52, such feed taking place when the rack is in its lower or normal position and being governed by an escapement, the teeth 53 of which alternately engage each successive tooth of the rack.

50 In the present instance the bar 36 consists of two parts, the upper one of which has an overhanging or rearwardly extending flange, while the lower part consists of the notched bar proper with which the escapement mechanism directly co-operates, it being understood that the stop 41 is formed or arranged on the upper part of the bar 36 in any suitable manner. The roller 37, which is arranged to oscillate in the manner hereinbefore described, co-operates with said flanged portion of the bar by pressing against the lower side or surface of such flange when the operating arm 46 is drawn forward to the dotted-line position shown 65 in Fig. 3. A pivoted lever 122^b is also pro-

vided, for raising the feed rack 36 off the escapement tooth.

The escapement is operated in the well known manner to feed the rack one step after each impression of a type, the movement forward of the reed-bar 12 carrying with it the transverse bar 54^a at the upper end of the vertical arm of an elbow lever 54, which elbow lever, through intermediate connections including the reciprocating rod 59, serves to oscillate the lever 60, mounted on the bar 61 pivoted between brackets 64 projecting from the track frame, and throws rearward the arm 62 which carries the teeth of the escapement, thus moving the teeth alternately in and out of engagement with the teeth of the rack and permitting the rack to be moved one space to the left as ordinarily done in typewriting machines. The space key 79 of the typewriter is also operatively connected with the rod 59 to operate the escapement mechanism in the same manner. The escapement arm 62 is provided at its upper end with a pivoted tooth 62^a, held upright by a spring 62^b, in order that such tooth may yield and slip over the teeth of the rack when moved to the left, but will rigidly engage and move the rack when moved forward.

It will be understood that in the combined typewriting and adding machine in which my invention is embodied, one carriage and platen suffices for both parts of the machine, the regular adding machine carriage being dispensed with. The platen of the carriage is provided with mechanism not directly involved in the present invention for turning it to cause a line-spacing feed of the paper, both manually through a lever 104, and as an incident of the regular adding and printing operation of the adding machine, through the operation of the operating handle 110^a of the adding machine, the feeding movement in this case taking place immediately after the printing is accomplished.

From the foregoing it will be seen that in my combined adding and typewriting machine an operator can insert a pay-roll, bill or any paper, and print a name or any descriptive matter with the typewriting machine, beginning at any point or number on carriage scale, after which the carriage may be quickly shifted longitudinally to any desired columnar position upon the adding machine which may be selected, it being understood that the operation of the push button 50 at the front of the machine and the consequent oscillation of the roller 37 and bar 36 causes disengagement between the escapement mechanism and such bar 36, and permits the carriage to advance to the columnar position which is predetermined by the position of the adjustable stop 44 on the bar 42. Any desired figures being then de- 125

pressed on the adding machine keyboard to set the type of the same in position, the printing of said figures is effected by the usual printing mechanism of such adding machine, such figures becoming a part of the line of printing done by the typewriting machine. It will be understood that the escapement is not operated, and the carriage does not move when the adding machine is operated, but the paper is automatically fed one line upward at the conclusion of the printing operation, as before stated.

While my invention is embodied in a combined adding and typewriting machine, it is obvious that the stop mechanism above described may be employed to position the carriage in a simple typewriting machine; also that it may be adapted to other combined typewriting and adding machines in which the printing points of the two machines face the platen in the same direction and in alignment, although the adding and typewriting mechanisms may differ from those above described, by suitable modification of the connecting and coöperating mechanism herein shown and described.

I claim:

1. The combination in a typewriting machine of the frame including rearwardly projecting stationary brackets, the carriage slidably mounted on the frame, rearwardly projecting arms pivoted to the carriage, the feed rack carried at the ends of the pivoted arms, a tabulating rail fixedly mounted in the rearwardly projecting brackets, removable stops on said tabulating rail, an arm pivoted in said brackets and projecting forwardly under the feed rack, and means for rocking the arm to raise the feed rack for contact with one of said stops.

2. The combination in a typewriting machine with the frame and the carriage slidably mounted thereon, of pivoted arms projecting rearwardly from the carriage, the feed rack carried at the ends of said pivoted arms and having a stop projection, a tabulating rail mounted in the frame in the rear of and above the normal position of the feed rack and having a stop projecting over the latter for coöperation with its stop projection, a lever pivoted in the frame in the rear of the rack and projecting forwardly under the same, and means for operating said lever to raise the rack from its normal position.

3. The combination in a typewriting machine with the frame and the carriage slidably mounted thereon, of arms pivotally mounted on the carriage, the feed rack secured to the arms, said rack being provided with an integral lug on its upper face and having a rearwardly projecting portion with smooth under surface, brackets projecting rearwardly from the frame, an arm pivoted in the brackets and projecting forwardly

and carrying a roller under said smooth surface, a tabulating rail mounted in the brackets and having rack teeth in its front and rear edges, a stop removably secured upon the tabulating rail and adjustable in its rack teeth, and means for operating the roller lever to raise the feed rack to bring its lug into line with said stop when in position on the rail.

4. The combination, with a longitudinally movable carriage and with escapement mechanism, of a longitudinal bar carried by and arranged to oscillate upon the carriage, said bar being normally under the control of the escapement mechanism, means for oscillating said bar at the will of the operator, and an adjustable fixed stop with which said bar is arranged to coöperate, the oscillation of the bar disengaging it from the escapement mechanism and moving a portion of it into line with said stop.

5. The combination, with a longitudinally movable carriage and with escapement mechanism, of a longitudinal bar carried by and arranged to oscillate upon the carriage, said bar being normally under the control of the escapement mechanism, means for oscillating said bar at the will of the operator, comprising a lever having one arm movable in the path of the bar, and an adjustable fixed stop with which said bar is arranged to coöperate, the oscillation of the bar disengaging it from the escapement mechanism and moving a portion of it into line with said stop.

6. The combination, with a longitudinally movable carriage and with escapement mechanism, of a longitudinal bar carried by and arranged to oscillate upon the carriage, said bar being normally under the control of the escapement mechanism, means for oscillating said bar at the will of the operator, comprising an operating arm, a roller thereon arranged to bear against said bar to oscillate the latter when said arm is actuated, and an adjustable stop with which said bar is arranged to coöperate, the oscillation of the bar disengaging it from the escapement mechanism and moving a portion of it into line with said stop.

7. The combination, with a longitudinally movable carriage, and with escapement mechanism, of a longitudinal bar carried by and arranged to oscillate upon the carriage, said bar being normally under the control of the escapement mechanism, means for oscillating said bar at the will of the operator, comprising a bell crank having one arm in the path of movement of the bar, a manually operated connection with the other arm thereof, and an adjustable stop with which said bar is arranged to coöperate.

8. The combination, with a longitudinally movable carriage and with escapement mechanism, of a longitudinal bar carried

by and arranged to oscillate upon the carriage, said bar being normally under the control of the escapement mechanism, means for oscillating said bar at the will of the operator, comprising a bell crank having one arm in the path of movement of the bar, a manually operated connection with the other arm thereof, a push button coöperating with said connection and within convenient reach of the operator, and an adjustable stop with which said bar is arranged to coöperate.

9. The combination, with a longitudinally movable carriage and with escapement mechanism, of a longitudinal bar carried by and arranged to oscillate upon the carriage, said bar having a portion coöperating with the escapement mechanism and another portion in the form of a flange, an operating arm in the path of said flange, and an adjustable stop with which said bar is arranged to coöperate.

10. The combination, with a longitudinally movable carriage and with escapement mechanism, of a longitudinal bar carried by and arranged to oscillate upon the carriage, said bar having a portion coöperating with the escapement mechanism and another portion in the form of a flange, an operating arm in the path of said flange, and an adjustable stop with which said bar is arranged to coöperate.

11. The combination, with a longitudinally movable carriage and with escapement mechanism, of a longitudinal feed bar with which the escapement mechanism coöperates, parallel side arms carrying said bar and mounted to oscillate on the carriage, an

operating arm in the path of said flange, 40 and an adjustable fixed stop with which said bar is arranged to coöperate.

12. The combination, with a longitudinally movable carriage and with escapement mechanism, of a longitudinal feed bar with 45 which the escapement mechanism coöperates, and which is mounted to oscillate on the carriage, means for oscillating the feed bar at the will of the operator, and a stationary bar having an adjustable stop with 50 which said feed bar coöperates.

13. The combination, with a longitudinally movable carriage and with escapement mechanism, of a longitudinal feed bar, with 55 which the escapement mechanism coöperates, and which is mounted to oscillate on the carriage, means for oscillating the feed bar at the will of the operator, a stationary bar having a series of notches along its length, and an adjustable stop arranged to be positioned in any one of said notches. 60

14. In a machine of the character described, the combination with a slidable carriage, escapement mechanism, a rack movably mounted on the carriage and normally 65 engaged with the escapement mechanism; of a fixed tabulator rail having one or more stops; and means for disengaging the rack from the escapement mechanism and thereby moving a portion of it into line with a stop 70 on the tabulator rail.

In testimony whereof, I affix my signature, in presence of two witnesses.
